Newton D. Robins.

UNITED STATES PATENT OFFICE.

NEWTON D. ROBINS, OF EDINBURGH, INDIANA.

COMBINATION OF AN AIR-CHAMBER, WATER-COOLER, AND FORCE-PUMP IN SODA-FOUNTAINS.

Specification of Letters Patent No. 12,489, dated March 6, 1855.

To all whom it may concern:

Be it known that I, NEWTON D. ROBINS, of Edinburgh, in the county of Johnson and State of Indiana, have invented a new and useful Portable Refrigerant Soda-Fountain; and I do hereby declare that the following is a full, clear, and exact description thereof, reference being had to the annexed drawings, making part of this specification, 10 in which—

Figure 1 is a vertical section through the center of the fountain in the line of the faucet, and Fig. 2 is a vertical section of the force pump in a line at right angles with 15 the above.

A, A, in Fig. 1 is a cooler having double walls with the intermediate space filled with charcoal.

A', A', is the space between the inner wall 20 and air chamber C, C, the latter is constructed of any metal and fixed to the bottom of the cooler by means of a female screw cut into the perforated nut s, s, which is soldered to the bottom of said air chamber at L, L, 25 and is adapted air tight to the male screw of pipe E, entering at this point H, through the bottom of the cooler into the air chamber. Another pipe F, is fixed firmly at any other point of the bottom of the cooler leading 30 into the space A', A'. About one-tenth of an inch above the bottom of the said air chamber at nut s, s, ascends a pipe R, which at the bottom is wider than the nut s, s, to admit the ascent of the fluid into the air 35 chamber and is narrowed toward the top where it is soldered to the air chamber at N, in which point a coupling screw attaches it to pipe R', furnishing into faucet R.

I, I, is the counter or a portable board 40 perforated in two places for the admission of pipes E, and F. B, B, B, is the cylinder of a force pump inclosed in the box D.

P, is the space between cylinder B, and said box D, filled out with plaster of Paris. 45 m, m, is another box surrounding box D, to collect the drippings, and to lead them off by the opening y. u, is the piston of the cylinder, and T, the handle of the piston—the arms of which handle move with their 50 extremities in the slides w, w, extending from box m, m, and fastened under the counter or board I, I, to prevent the piston u, from being bent.

Pipes x, and o, are fixed to the cylinder 55 and connected by coupling screws to the

pipes F, and E, and provided at the coupling points with valves. A valve may also be provided for the pipe E, at H.

Mode of operation, I fill space A', A', with ice, water and carbonate of soda about 60 in the proportion of one ounce to the gallon of water, ice included. I then force the desired quantity thereof into the air chamber from which it may be served by the faucet k, into tumblers wherein the syrup is previously charged with the necessary quantity of acid for effervescence. 65

I do not claim originality for any single part of the above device, when isolated from the rest, as I am aware that they are all old. 70 But as all known forms of soda founts are liable to the following objections: 1st, they are expensive and require great skill to charge and manage them; 2nd, they are unwieldy, and from their extended parts occupy too much space; 3rd, from the last consideration, and their fixed nature, they are not portable, cannot be moved conveniently from room to room nor transported, for the convenience of public audiences, and 4th, in their use the ice is not economized nor is the beverage so palatable, because the chemicals are separated from the ice, by pipes, cylinders, &c., in which they stand in the interim. And inasmuch as combining an air 75 chamber within a water cooler, and connected with a force pump substantially as above, produces the following results (and is new): 1st, a cheap soda fount in the reach of the masses and that can be charged and managed by any person. 2nd, a light concentrated fount that occupies but little space in contrast with others. 3rd, from the last consideration it is one that is preëminently 80 portable by even a boy—may be moved from cellar to parlor, from parlor to garret or may itinerate, to suit the convenience of public assemblies. 4th, the ice being surrounded by a nonconductor of caloric, is 85 protected from the high temperature of the atmosphere, so that but little is required and it in its turn envelopes the air chamber through which all the ingredients must pass before their exit. Thus the alkaline solution (being mixed with the ice) is kept cool, 90 the air in the bosom of the ice is cool, and the ice itself is prevented from melting by the most approved nonconductors of heat. 95

100 And the small amount of metallic pipe used, to conduct the fluid from the ice chamber to 105 110

the faucet. Thus, in two particulars, both as to quantity of ice, and pipe, economizing.

The unparalleled simplicity of arrangement, the concentration of parts, in this apparatus, and its cheapening qualities, will enable thousands to partake of a luxury of which they have hitherto been deprived. Therefore what I claim is not the water cooler, the air chamber, the force pump, the connecting pipes, nor the making of soda water with chemicals under atmospheric pressure, but

What I do claim as my invention, and desire to secure by Letters Patent, is—

The apparatus as constructed of a combination of a water cooler A, A, an air chamber C, C, placed within A', A', and force pump B, B, and made to operate substantially as herein before specified. 15

NEWTON D. ROBINS.
